UNITED STATES PATENT OFFICE.

FRANK J. BECK, OF BOSTON, MASSACHUSETTS.

DRAPERY-SUPPORTING RING.

Application filed September 8, 1923. Serial No. 681,579.

To all whom it may concern:

Be it known that I, FRANK J. BECK, a citizen of the United States, residing at Boston, in the county of Suffolk and State 5 of Massachusetts, have invented certain new and useful Improvements in Drapery-Supporting Rings, of which the following is a specification.

This invention relates to drapery supporting rings and has particular reference to rings adapted to be disposed upon curtain poles and provided with means for engaging a curtain or portière or the like for suspending the latter from the pole.

15 The primary object of the invention is to provide a ring of the above kind, which embodies the desired qualities of simplicity, durability, and efficiency in operation.

Another object of the invention is to provide a ring composed of hingedly connected half sections respectively provided with opposed depending jaw members that are moved toward each other upon closing of the ring for gripping the curtain or portière.

25 A further object of the invention is to provide jaw members which cross each other and are rigidly fastened to the adjacent ends of the ring section as well as hingedly connected to each other for forming the pivotal connection between the sections of the ring.

Other objects will appear as the nature of the invention is better understood, and the same consists in the novel form, combination and arrangement of parts herein- 35 after more fully described, shown in the accompanying drawing and claimed.

In the drawing, wherein like reference characters indicate corresponding parts throughout the several views.

Figure 1 is a side elevational view of a drapery ring constructed in accordance with the present invention.

Figure 2 is an edge elevational view of the device shown in Figure 1, and

Figure 3 is a substantially central sectional view thereof.

Referring more in detail to the drawings, the present invention comprises a ring member embodying a pair of half sections 5 and 6, adjacent ends of which at the bottom of the ring are hingedly connected as at 7, by means of a rivet or pin whereby the sections may be swung away from each other for facilitating application of the ring to the curtain pole or removal thereof from the

curtain pole, and for separating the jaw members of the device as will presently become apparent, means being provided for detachably connecting the other ends of the 60 ring sections 5 and 6 at the top of the ring as indicated generally at 8.

In the preferred form of the invention, the ring sections 5 and 6 are preferably composed of arcuate tubes, and the means for 65 detachably connecting the upper ends of the sections preferably embodies a relatively short tube or tubular keeper 9 that is inserted within the end of the section 6 and suitably secured in place, by riveting, soldering, brazing or the like, so that one end of the tubular keeper 9 projects outwardly beyond the end of the section 5 as shown clearly in Figure 3. The projecting end of the keeper 9 has an opening as at 10 for 70 reception of the hooked end of the catch 8 that is of a resilient construction riveted within the adjacent end of the section 6 as at 11. This catch 8 normally springs outwardly to engage its hooked end in the 75 opening 10 and may be manually released by means of a finger piece or button 12 that is attached thereto and slidably projects through the ring section 6 as shown.

The hinge connection 7 between the ring 85 sections 5 and 6 embodies a pin that extends through the cross portion of a pair of angular jaw members 13 that are rigidly fastened to the pivotally connected end of the ring section, and these jaw members are 90 preferably formed of channel shaped sheet metal with the flanges thereof facing each other. Suitably fixed within the channels of the depending portions of the jaw members 13 are serrated face gripping blocks 14, 95 which may be constructed of vulcanized rubber, if desired, for preventing tearing or marring of the drapery, the web of the channel of each jaw member being cut away at the upper portions of the jaws to leave 100 the flanges positioned against the sides of the ring sections 5 and 6 where they are 105 suitably rigidly secured to said sections by soldering, brazing or otherwise.

In use, the finger piece 12 is pressed inwardly for releasing the catch 8 from the keeper 9 whereupon the sections 5 and 6 may be swung away from each other for opening the ring and separating the jaw members 13. When thus opened, the ring may be 110 readily applied to the curtain pole and the drapery may be readily inserted between

the jaws. The ring sections 5 and 6 may then be swung toward each other so that the projecting end of the keeper 9 slides into the open end of the section 6 and the catch 8 snaps into engagement with the opening 10 of said keeper, whereby the sections are effectively retained against accidental separation. When the sections of the ring are thus closed or swung together, 10 the jaws 13 are likewise caused to move toward each other by reason of their rigid connection to the ring section and the crossing of the same at the pivot 7, thus moving the jaws 13 into gripping engagement with 15 the drapery for effectively retaining and supporting the latter. In order to permit the swinging movement of the ring sections, the adjacent ends of the same are cut away as indicated at 15, in Figure 3, adjacent the 20 pivotal connection 7.

In view of the above, it will be seen that I have provided a simple, durable and efficient form of curtain or portière supporting ring which may be readily engaged with the 25 pole and the drapery and which may be manufactured and furnished to the public

at a relatively low cost as a more desirable substitute for the objectionable pin carrying rings now in general use.

Minor changes may be made without departing from the spirit and scope of the invention as claimed.

What I claim as new is:

A drapery supporting ring comprising a pair of tubular semi-circular sections provided at one end with radially disposed end edges and provided at their opposite ends with beveled end edges, jaws fixed to the sections at the beveled ends thereof, the intermediate portions of the jaws being disposed transversely of each other and pivoted together, the pivots occurring between the beveled ends of the sections, said jaws having pockets disposed substantially radially with relation to the sections, gripping blocks located in the pockets of the jaws and interengageable catch members located inferiorly of the sections at the radially disposed end edges thereof.

In testimony whereof I affix my signature.

FRANK J. BECK.
